ENGINE CONTROL MECHANISM

Thomas Clarence Wallace, Ventura, Calif.

Application April 30, 1948, Serial No. 24,401

12 Claims. (Cl. 123—103)

1

My invention relates to a motor or engine control mechanism.

One of the principal objects of this invention is to provide a control mechanism for motors, and particularly for engines of various types, for stopping or checking the operation thereof, or for restricting the operation thereof to definite speed limits, either to a definite or predetermined high speed of the engine, low speed of the engine or failure of the control mechanism, or in the occurrence of all of such events.

An important object of this invention is to provide a control mechanism for shutting down the motor or engine, in the event of the motor or engine attaining excessive speed, by rupturing the electrical system thereof.

An important object of this invention also is the provision of a control mechanism for engines whereby the fuel line to the engine is closed or regulated to prevent excessive or predetermined speed, or which causes failure of the fuel line in event of failure of the control mechanism.

A further important object of this invention is to provide a control mechanism of this class, which is relatively simple and economical of construction and operation, and which will not readily get out of order.

With these and other objects in view, as will appear hereinafter, I have devised a control mechanism for motors having certain novel features of construction, combination, and arrangement of parts and portions, as will be herein-after described in detail, and particularly set forth in the appended claims, reference being had to the accompanying drawings and to the characters of reference thereon, which form a part of this application, in which:

Fig. 1 is a schematic view of my control mechanism as applied to an internal combustion engine for controlling the engine by the control of the ignition system thereof;

Fig. 2 is an enlarged sectional view thereof, showing my control unit in a preferred form, the section being taken through 2—2 of Fig. 3;

Fig. 3 is a sectional elevational view thereof, taken through 3—3 of Fig. 2;

Fig. 4 is an enlarged sectional elevational view, showing a form of high pressure switch for controlling or regulating the high speed of the engine;

Fig. 5 is an enlarged sectional view showing one form of the low pressure switch for controlling the engine in the event of failure of the control mechanism; and,

2

Fig. 6 is a schematic view, showing, in one form, my control mechanism applied to the fuel control system of an internal combustion engine.

The principal control unit of my mechanism, 5 as shown in Figs. 2 and 3, is enclosed in a housing consisting of housing members 1 and 2, the former being in the form of a container, while the principal part of the latter fits within the former, one end of the latter forming a cover 2^a which is secured over the upper open end of the container one.

Within the housing member 1 is mounted the pump, which is, in this instance, a gear pump consisting of meshing spur gears 3 and 4, one 15 side of the gear housing 2^b being connected at its lower side through a passage 2^c to a reservoir 1^a below the housing member 2, and connected at its upper side through an upwardly directed passage 2^d. This passage 2^d has near its upper end 20 a transverse passage 2^e having connected thereto passages 2^f and 2^g which extend through the upper or cover portion 2^a of the housing member 2. These passages 2^f and 2^g are connected to or provide connections for a high pressure switch 25 A and a low pressure switch B, respectively, as will be described hereinafter.

The high pressure side of the pump, through the passage 2^e, is connected to the reservoir 1^a surrounding the lower portion of the housing member 2 within the housing member 1, one end of the passage 2^e forming a by-pass with the reservoir 1^a. In this end of the passage 2^e is provided a controlled by-pass valve comprising a by-pass valve casing 5 and a needle valve 6, the 30 end of the casing 5, which extends into the passage 2^e, being provided with a port 5^a, and the lower side of the casing 5, beyond the housing member 2, being provided with a side opening 5^b. The needle valve 6 is axially adjustable within the casing 5 for controlling the side of the discharge port 5^a.

In the wall of the housing member 1 is a plug 7, which plug is in alignment with the needle valve 6. Removal of this plug permits adjustment of the needle valve for controlling the discharge port 5^a, and thereby controlling the effective pressure upon the high and low pressure switches A and B. The gears 3 and 4 of the gear pump have shafts 8, which extend through and beyond one side of the lower portion or block of the housing member 1. The gear pump is driven by a shaft 9 which extends through the side wall of the housing member 1 and is connected at its inner end by gears 10 and 11 to one of the shafts 50 8. Reversal of the gear 11 to one or the other

of the shafts 8 permits the gear pump to be rotated in opposite directions, depending upon the available connection of the unit to the engine which it is adapted to control.

As shown, the shaft 9 is connected by a shaft 12 through bevel gears 13 to the engine 14.

The control unit is designed to operate under various temperature conditions, and for this reason fluid with a flat viscosity characteristic is employed so that it may be effectively used for temperatures considerably below zero and above the boiling point of water.

The high pressure switch, designated A, is enclosed in a casing 21, which is connected by means of a pipe 22 to the passage 2^f communicating with the high pressure side of the pump. Within the casing 21 is a diaphragm 23 which is under the influence of the fluid pressure within the passage 2^f. Within the casing is a switch mechanism which may be in the form of a microswitch 24 having a flexible contact 25, which under normal conditions is separated from a stationary contact 26.

The engine 14, illustrated in Fig. 1, is shown provided with the usual spark plug 27 which is shown energized by a source of energy such as a battery 28, this battery being connected by a wire 29 through various intermediate elements to the spark plug 27, and by a wire 30 to the ground. The contact 25 of the microswitch is connected by a wire 31 to the wire 29 of the ignition circuit, and the contact 26 is connected to the same ground, as above mentioned. Excessive predetermined pressure within the pump housing causes the diaphragm 23 to be expanded and the contact 25 to engage the contact 26, and thereby ground the ignition circuit of the engine and thus shut down the latter.

The low pressure switch B is designed so that it normally grounds the ignition circuit, but fluid pressure from the gear pump opens the contacts so that the engine may operate freely. It is, however, designed so that rupture of the fluid pressure line will cause dropping of the fluid pressure so that the ignition circuit is also grounded, thereby shutting off the engine.

This low pressure switch is enclosed in a casing 51 having a diaphragm 52 which is directly subject to the pressure in the passage 2^g. This diaphragm carries a contact 53 which is spring biased toward a stationary contact 54, and normally engages the same until separated by pressure from the pump. The contact 53 has an arm or plunger 55, which extends to the exterior of the casing 51 and is provided at its extended end with a spring arm 56. This spring arm is adapted to be distorted, as shown by dotted lines in Fig. 5, for separating the contacts 53 and 54 when starting the engine.

When the engine is started the spring arm 56 is unseated and the contacts 53 and 54 are held apart by the pressure of the pump. Rupture of the pressure line forces the contact 53 to engage the contact 54 by means of a spring 57. As shown, the contact 53 is connected to ground wire, and the contact 54 is connected by a wire 58 to the wire 29 of the ignition circuit.

Similar control mechanism, as described above, is applied for the control of the fuel line of an internal combustion engine, shown in the schematic view of Fig. 6. The ordinary internal combustion engine or diesel engine is controlled by a butterfly valve C, a fuel rack D, and a fuel pump E. These are intended to be directly controlled by my control mechanism having a low pressure valve mechanism F and a high pressure

or over-speed valve mechanism G. The low pressure valve mechanism F is enclosed in a casing 61 having chambers 61^a and 61^b separated by a wall 61^c having a normally closed valve 64. The valve 64 is shown connected by a rod 65 to a diaphragm 66 enclosed in a housing 67. This housing is connected by a conductor 68 to the high pressure side of the pump, and normally acts upon the diaphragm to close the valve 64 against the action of a spring 69. The conductor 68 is also connected by a conductor 70 to the chamber 61^a, which is connected by a conductor 71 to a chamber 72^a of a casing 72 of the high pressure or over-speed valve mechanism G.

The casing 72 has chambers 72^a, 72^b, and 72^c, formed by transverse walls 72^d and 72^e. Over ports in the partial walls 72^d and 72^e are operatively mounted valves 73 and 74 which are axially connected, one of the valves being open when the other is closed. At one end of the casing 72 is a diaphragm housing 75 in which is mounted a diaphragm 76 which is connected by a rod 76^a to the valves 73 and 74. These valves are so mounted that normal operating pressure of the pump allows the valve 73 to remain open and the valve 74 to remain closed over the ports of the respective walls, the valves being forced to assume such position by means of a spring 77. It will be noted that the diaphragm housing 75 is connected by a conductor 78 with the high pressure side of the pump.

With the system as described and the pump operating at normal pressure, the valves 64 and 74 are closed and the valve 73 is open, allowing fluid pressure from the pump to pass through the conductor 70 into the chamber 61^a, through the conductor 71, past the valve 73, into the chamber 72^b and into conductors 79, 80, 81, and 82, for operating, by means of pressure activated diaphragms, the control for the butterfly valve C, fuel rack D, and the fuel pump E.

The valves 85 and 86 of the fuel rack control D and the pump E are held open during normal operation of the pump F against the action of the springs 87 and 88, shown in Fig. 6, by fluid pressure in the lines 81 and 80. The butterfly valve C is normally latched in open position against the spring 89 by means of a latch device 90, in response to normal operating pressure in the line 82, the latch device being pivoted at 91.

When the pressure of the pump exceeds a predetermined high pressure, the condition of the valve 64 is not altered, but the valve 73 is closed and the valve 74 is opened. With the fluid pressure thus relieved in the line 79, the valves 85 and 86 are permitted to close under the action of the springs 87 and 88 so as to stall the engine. This permits the fluid under pressure from the conductors 79, 80, 81, and 82, to return past the valve 74 through a conductor 83 connecting the chamber 72^c with the chamber 61^b, and thence through a conductor 84 into the reservoir of the pump. With the pressure thus relieved, the spring 89 releases the latch 90 to allow the butterfly valve to close.

Rupture of the conductors of the control mechanism, or any of the conductors connected therewith, causes the valve 64 to become unseated and the fluid to return to the reservoir of the pump, or to neutralize both sides of the pump, and thereby render inoperative the valves of the engine.

I wish it to be understood that I do not desire to be limited to the exact details of construction shown and described, for obvious modifications will occur to a person skilled in the art. The

terms used herein are to be construed as including control mechanisms for engines and motors in general, and whether such control mechanisms are valves or switches.

I claim:

1. In a control mechanism of the class described for a motor having an electric operating circuit, a pump adapted operatively to be connected to the motor, the pump having a discharge and an inlet, a controlled by-pass for connecting the discharge to the inlet, and a liquid pressure controlled switch connected to the discharge of the pump, said switch having spaced contacts arranged to be connected to the circuit, predetermined pressure at the discharge side of the pump on the switch closing the contacts to short the circuit of the motor.

2. In a control mechanism of the class described for a motor having an electric operating circuit, a pump adapted operatively to be connected to the motor, the pump having a discharge and an inlet, a controlled by-pass for connecting the discharge to the inlet, and a liquid pressure controlled switch connected to the discharge of the pump, said switch having normally open contacts arranged to be connected to the circuit, predetermined pressure at the discharge side of the pump on the switch closing the contacts to short the circuit of the motor.

3. In a control mechanism of the class described for a motor having an electric operating circuit, a pump adapted operatively to be connected to the motor, the pump having a discharge and an inlet, a controlled by-pass for connecting the discharge to the inlet, and a liquid pressure controlled switch connected to the discharge of the pump, said switch having normally closed contacts arranged to be connected to the circuit, pressure at the discharge side of the pump on the switch opening the contacts, and loss of pressure again closing the contacts to short the circuit of the motor.

4. In a control mechanism of the class described for an engine having an electric ignition circuit, a pump adapted operatively to be connected to the engine, the pump having a discharge and an inlet, a controlled by-pass for connecting the discharge to the inlet, and a liquid pressure controlled switch connected to the discharge of the pump, said switch having spaced contacts arranged to be connected to the circuit, predetermined pressure at the discharge side of the pump on the switch closing the contacts to short the circuit of the engine.

5. In a control mechanism of the class described for an engine having an electric operating circuit, a pump adapted operatively to be connected to the engine, the pump having a discharge and an inlet, a controlled by-pass for connecting the discharge to the inlet, and a liquid pressure controlled switch connected to the discharge of the pump, said switch having normally open contacts arranged to be connected to the circuit, predetermined pressure at the discharge side of the pump on the switch closing the contacts to short the circuit of the engine.

6. In a control mechanism of the class described for an engine having an electric operating circuit, a pump adapted operatively to be connected to the engine, the pump having a discharge and an inlet, a controlled by-pass for connecting the discharge to the inlet, and a liquid pressure controlled switch connected to the discharge of the pump, said switch having normally closed contacts arranged to be connected to the

circuit, pressure at the discharge side of the pump on the switch opening the contacts, and loss of pressure again closing the contacts to short the circuit of the engine.

5. 7. In a control mechanism of the class described for a motor having an electric operating circuit, a pump adapted operatively to be connected to the motor, the pump having a discharge and an inlet, a controlled by-pass for connecting the discharge to the inlet, and a pair of liquid pressure controlled switches connected to the discharge side of the pump, one switch having a set of normally open contacts and the other having a set of normally closed contacts, the contacts of each switch being arranged to be connected to the circuit, normal pressure at the discharge side of the pump holding both sets of contacts open, predetermined high pressure closing the first set of contacts and predetermined low pressure closing the second set of contacts, closing of either set shorting the motor circuit.

8. In a control mechanism of the class described for an engine having an electric ignition circuit, a pump adapted operatively to be connected to the engine, the pump having a discharge and an inlet, a controlled by-pass for connecting the discharge to the inlet, and a pair of liquid pressure controlled switches connected to the discharge side of the pump, one switch having a set of normally open contacts and the other having a set of normally closed contacts, the contacts of each switch being arranged to be connected to the circuit, normal pressure at the discharge side of the pump holding both sets of contacts open, predetermined high pressure closing the first set of contacts and predetermined low pressure closing the second set of contacts, closing of either set shorting the engine circuit.

9. In a control mechanism of the class described for an engine, said engine having a source of fuel supply, a pump adapted operatively to be connected to the engine, the pump having a discharge and an inlet, a controlled by-pass for connecting the discharge to the inlet, a liquid pressure fuel-supply control means connected to the discharge side of the pump for controlling the engine, said means having normally separated control members to allow flow of fuel to said engine, predetermined high pressure from said pump to said means closing said members toward each other to prevent said flow and to shut off the engine.

10. In a control mechanism of the class described for an engine, a pump adapted operatively to be connected to the engine, the pump having a discharge and an inlet, a controlled by-pass for connecting the discharge to the inlet, a liquid pressure control means connected to the discharge side of the pump for controlling the engine, said means having normally closed control members for said engine, predetermined high pressure from said pump to said means opening said members to shut off the engine.

11. In a control mechanism of the class described for an engine having an electric operating circuit, a pump adapted operatively to be connected to the engine, the pump having a discharge and an inlet, a controlled by-pass for connecting the discharge to the inlet, and a pair of liquid pressure control means connected to the discharge side of the pump, one of the control means having normally open members and the other having normally closed members, normal pressure at the discharge side of the pump holding both sets of members open, predetermined

high pressure from the pump to the means closing the first set of members and predetermined low pressure from the pump to the means closing the second set of members, closing of either set of members causing shutting down of the engine.

12. In a control mechanism for an engine: a pump operatively connected to the engine to be driven thereby, means defining a closed fluid system through which fluid is circulated by said pump, said system being independent of the lubricating system of the engine and extending from the discharge side of the pump to the inlet side thereof, means defining a set, restricted orifice in said system, the portion of the system between the discharge side of the pump and said orifice constituting a high pressure chamber and the portion of the system between the orifice and the inlet side of the pump being a low pressure chamber, fluid-pressure-actuated control means in fluid communication with said high pressure chamber, said control means having control members operatively connected to the engine and relatively movable toward and away from each other, said control members being normally maintained in spaced relationship in response to

5

10

a predetermined normal range of pressures in said pressure chamber as effected by the engine-driven pump when the engine is operating within a normal range of speeds so as to maintain the engine operative, increase in fluid pressure in said pressure chamber beyond said normal range, as effected by increase in speed of the engine beyond its normal speed range, causing said control members to engage each other so as to stall the engine.
